(57) **CLAIM**

The ornamental design for a spout for a packaging, as shown and described.

DESCRIPTION

FIG. 1 is a left front perspective view of the spout for a packaging, in a fully extended position;

FIG. 2 is a left front perspective view thereof, in a partially extended position;

FIG. 3 is a right bottom perspective view thereof, in a fully retracted position;

FIG. 4 is a front view thereof, in the fully extended position;

FIG. 5 is a front view thereof, in the partially extended position;

FIG. 6 is a front view thereof, in the fully retracted position;

FIG. 7 is a top view thereof, in the fully extended position;

FIG. 8 is a top view thereof, in the partially extended position;

FIG. 9 is a top view thereof, in the fully retracted position;

FIG. 10 is a left side view thereof, in the fully extended position;

FIG. 11 is a left side view thereof, in the partially extended position; and,

FIG. 12 is a left side view thereof, in the fully retracted position.

In the drawings, the broken lines show portions of a spout for a packaging that form no part of the claimed design.
